(57) **CLAIM**

The ornamental design for a vehicle tie-down unit, as shown and described.

DESCRIPTION

FIG. 1 is a perspective view of a vehicle tie-down unit showing our new design;

FIG. 2 is a side elevational view thereof;

FIG. 3 is an elevational view of the opposite side thereof;

FIG. 4 is an end elevational view thereof;

FIG. 5 is an elevational view of the opposite end thereof;

FIG. 6 is a top plan view thereof;

FIG. 7 is a bottom plan view thereof; and,

FIG. 8 is a reduced side elevation view showing the vehicle tie-down unit in use; the broken lines depict environmental structure for illustrative purposes only and form no part of the claimed design.
